Primary Examiner—Brian N. Vinson*Attorney, Agent, or Firm*—I. C. Waddey, Jr.**[57] CLAIM**

The ornamental design for a shelving assembly, as shown and described.

DESCRIPTION

FIG. 1 is a top and front perspective view of a shelf assembly showing my new design, the broken-line disclosure of a portion of a wall being for illustrative purposes only and forming no part of the claimed design; and

FIG. 2 is a reduced right side elevational view thereof.
